UNITED STATES PATENT OFFICE

154,066

DESIGN FOR A LAMP WITH ILLUMINABLE
BASE

Joseph Provenzano, New York, N. Y.

Application December 24, 1948, Serial No. 150,344

Term of patent 7 years

(Cl. D48—20)

To all whom it may concern:

Be it known that I, Joseph Provenzano, a citizen of the United States of America, residing in New York city, county of New York, and State of New York, have invented a new, original, and ornamental Design for a Lamp with Illuminable Base, of which the following is a specification, reference being had to the accompanying drawing, forming part thereof, wherein,

Figure 1 is a front perspective view of a lamp with illuminable base, showing my new design.

Figure 2 is a rear elevational view thereof, drawn on a smaller scale.

The characteristic features of my design reside in the portions shown in full lines in the drawing.

I claim:

The ornamental design for a lamp with illuminable base, substantially as shown and described.

JOSEPH PROVENZANO.
